TEST TUBE RACK

Philip M. Seymour, Ann Arbor, Mich.

Application February 5, 1958, Serial No. 49,508

Term of patent 14 years

(Cl. D58—13)

Figure 1 is a top plan view of a test tube rack showing my new design;

Figures 2 and 3 are a front elevational view and a bottom plan view thereof, respectively; and

Figure 4 is a sectional view taken on the line 4—4 of Figure 1.

The sides not shown are plain.

I claim:

The ornamental design for a test tube rack, as shown and described.
